UNITED STATES PATENT OFFICE

170,313

ENGINE PRIMING DEVICE

George E. Franck, Riverside, Ill., assignor to The
Imperial Brass Manufacturing Company, Chi-
cago, Ill., a corporation of Illinois

Application September 11, 1952, Serial No. 21,421

Term of patent 14 years

(Cl. D77—1)

To all whom it may concern:

Be it known that I, George E. Franck, a citizen of the United States, residing at Riverside, in the county of Cook and State of Illinois, have invented a new, original, and ornamental Design for an Engine Priming Device, of which the following is a specification, reference being had to the accompanying drawing, forming a part hereof.

In the drawing:

Fig. 1 is a side elevational view of an engine priming device embodying my new design.

Fig. 2 is a front elevational view of the device of Fig. 1.

Fig. 3 is a top plan view of the device of Fig. 1.

I claim:

The ornamental design for an engine priming device, as shown.

GEORGE E. FRANCK.
